UNITED STATES PATENT OFFICE.

NELS KROHN, OF CHICAGO, ILLINOIS, ASSIGNOR TO THE ADAMS & WESTLAKE COMPANY, A CORPORATION OF ILLINOIS.

PADLOCK.

1,348,884.

Specification of Letters Patent. Patented Aug. 10, 1920.

Application filed May 17, 1919. Serial No. 297,751.

To all whom it may concern:

Be it known that I, NELS KROHN, a citizen of the United States, and resident of Chicago, county of Cook, and State of Illinois, 5 have invented certain new and useful Improvements in Padlocks, of which the following is a specification, and which are illustrated in the accompanying drawings, forming a part thereof.

10 The invention relates to padlocks especially adapted for use in connection with switch mechanism for railroads; its objects being to provide a lock which shall be reliable in action and difficult to be released 15 except by means of a specially designed key.

In railroad practice it is essential that switches be securely locked against dishonest persons who may seek to throw the switch against an approaching train for the purpose 20 of disabling it. It has been found that many of the locks in common use may be opened by a blow from a hammer or similar implement, such blow, if skilfully delivered, causing the retraction of the bolt. While 25 many efforts have been made to produce a lock which shall be safe against such tampering, they have not been entirely successful.

The present invention consists of a lock 30 organized substantially as hereinafter described and as illustrated in the accompanying drawings, in which—

Figure 1 is a face elevation of the lock;

Fig. 2 is a view of the lock with the face 35 plate removed, the shackle being closed;

Fig. 3 is a similar view, the shackle being open;

Fig. 4 is a sectional view on the line 4—4 of Fig. 3;

40 Fig. 5 is a view in perspective of the bolt; and

Fig. 6 is a view in perspective of the key adapted to open the lock.

The shell or casing 10 of the lock is of 45 ordinary form, and is provided with a face plate 11 permanently secured thereto by means of suitable rivets, as 12. The shackle 13 is of the usual arch form and is pivoted at 14 between a pair of lugs, as 15, upstanding from the side faces of the shell and between which there is an aperture 16, into which a portion of the hub of the shackle enters.

The shell is also provided with a suitable 50 aperture to receive the nose 17 of the shackle,

which is provided with an aperture 18 to receive the locking bolt 19. The bolt 19 is advanced by means of a suitable spring 20, here shown as coiled about a post 12 which serves as one of the rivets for securing the 60 face plate as described. The rear end of the bolt extends below the hub of the shackle, and is provided with a flattened upper face 21 for engaging a flattened portion 22 of the hub when the shackle is closed. The lower 65 margin 23 of the rear portion of the bolt has a straight face parallel to the flattened portion 22 and bearing against a fixed post 24, the rear end of the bolt being thus rigidly held against vibration between the shackle 70 hub and the post 24 when the shackle is closed.

A wing 25, depending from the body portion of the bolt, is provided with a curved shoulder 26 for engagement by the key for 75 the purpose of retraction. A stem 27, projecting forwardly from the wing 25, underlies a post 28 upon which the forward end of the bolt rides and is guided. The rearward end of the stem 27 is provided with a shoulder 29, projecting laterally from the wing 25, and adapted to be engaged by a spring-advanced latch 30 pivoted on the post 24. The rearward end of the latch 30 is provided with a downwardly projecting toe 31, against 80 which bears a spring 32 for holding the latch in engagement with the shoulder 29. The springs 20 and 32 may be conveniently formed, as shown, of a single piece of wire coiled about the post 12. 90

A securing latch 33 is pivotally attached to the latch 30, and engages as a hook a post 34, being urged into such engaging position by means of a spring 35, coiled about the post 34 and bearing upon a stud 36 se- 95 cured to the latch.

The shackle is spring-retracted, there being shown for this purpose a spring 37, coiled about a post 38, one end thereof bearing against the end of the shackle nose and 100 the other against the edge wall of the shell. A key post is shown at 39, and may be surrounded by an upstanding annular flange 40, to prevent the insertion of a key not properly configured to receive it. A suitable 105 aperture 41 is formed in the face plate 11 to receive the key 42. This key is provided with suitable wards 43 for engaging the latches 33 and 30 and the shoulder 26 of the bolt 19. 110

In its initial turning movement the key disengages the latch 33 from the post 34 and holds it in retracted position against the resistance of the spring 35, until by the 5 further movement of the key the latch 30 is raised out of engagement with the bolt shoulder 29, thereby bringing the hook of the latch 33 above the post 34, as shown in Fig. 3. Further movement of the key causes 10 its engagement with the shoulder 26 of the bolt, withdrawing the latter against the resistance of the spring 20, releasing the shackle and permitting its ejection by the spring 37. The flattened face 22 of the 15 shackle hub swings into a recess 44 formed in the upper face of the bolt in advance of its flattened portion 21, and prevents the advance of the bolt until the shackle is again closed. A depending lug 45 is preferably 20 formed on the hub of the shackle to overlie the bolt and hold it against lateral vibration.

Inasmuch as it is essential that the latch 33 be held in retracted position until the latch 30 is raised, and both of these latches 25 must be held in withdrawn positions until the bolt is retracted, the releasing of the lock by any instrument other than a properly fitting key is rendered exceedingly difficult. The release of the lock by jars, as by the 30 blow of a hammer, is rendered practically impossible because the parts to be released move in three different directions. Furthermore, to release the lock by a blow would involve simultaneous movement of the several parts, which is impossible as the latch 35 30 must necessarily move in advance of the bolt. If the latch 33 were jarred out of engagement with the post 34, the latch 30 would still be held in engagement with the shoulder 29, and before its disengagement could be effected the latch 33 would have been returned into engagement with the post by the action of the spring 35.

While I have shown a preferred and efficient form of construction, various changes 45 of detail might be made without departing from the scope of the invention.

I claim as my invention—

1. In a padlock, in combination, an oscillating shackle, a reciprocating spring-advanced bolt for securing the shackle, means movable in the arc of a circle transversely to the path of the bolt for holding the bolt in advanced position, and key-releasable 50 means for securing the last-named means in engagement with the bolt.

2. In a padlock, in combination, an oscillating shackle, a reciprocating spring-advanced bolt for securing the shackle, spring-advanced means movable in the arc of a circle transversely to the path of the bolt for holding the bolt in advanced position, and key-releasable means carried by the last-named means for securing the same in 55 engagement with the bolt.

3. In a padlock, in combination, an oscillating shackle, a reciprocating spring-advanced bolt for securing the shackle, spring-advanced and key retracted means movable transversely to the path of the bolt for holding the bolt in advanced position, and key-releasable means carried by the last-named means for securing the same in engagement with the bolt. 70

4. In a padlock, in combination, an oscillating shackle, a reciprocating spring-advanced bolt for securing the shackle, means movable transversely to the path of the bolt for holding the bolt in advanced position, a spring-advanced key-retracted latch carried 75 by such means, and a fixed keeper for the latch.

5. In a padlock, in combination, an oscillating shackle, a reciprocating spring-advanced bolt for securing the shackle, a spring-advanced oscillating latch adapted 80 to engage back of a shoulder on the bolt and movable transversely of the path of the bolt, a key-releasable latch pivotally carried by the previously named latch and movable transversely to the path thereof, and a fixed keeper for the last-named latch. 85

6. In a padlock, in combination, an oscillating shackle, a reciprocating spring-advanced bolt for securing the shackle, a spring-advanced key-retracted oscillating latch adapted to engage back of a shoulder on the bolt and movable transversely to the path of the bolt, a key-releasable latch pivotally carried by the previously named latch and movable transversely to the path thereof, and a fixed keeper for the last-named latch. 95

7. In a padlock, in combination, an oscillating shackle, a reciprocating spring-advanced bolt for securing the shackle and being held in retracted position by the shackle when the latter is open, means movable transversely to the path of the bolt for holding the bolt in advanced position, and key-releasable means for securing the last-named means in engagement with the bolt. 105

8. In a padlock, in combination, an oscillating shackle, a reciprocating bolt for securing the shackle, means movable in the arc of a circle transversely into and out of the path of the bolt for holding the bolt in advanced position, and key-releasable means for securing the last-named means 110 in engagement with the bolt. 115

9. In a padlock, in combination, an operable shackle, a movable bolt for securing the shackle, means movable in the arc of a circle transversely into and out of the path 120 of the bolt for holding the bolt in advanced position, and key-releasable means for securing the last-named means in engagement with the bolt. 125

10. In a padlock, in combination, an os- 130

cillating shackle, and three coöperating elements for securing the shackle in closed position, all of such three elements being movable in different directions for releasing the shackle, two of said elements being oscillatable.

11. In a padlock, in combination, an oscillating shackle, a movable bolt for securing the shackle, and a lug projecting from the hub of the shackle and overlying the bolt to prevent lateral movement thereof.

12. In a padlock, in combination, a casing, a shackle pivoted to said casing, a bolt guiding post and a spring receiving post located on opposite sides of the closed position of the nose of said shackle, a shackle expelling spring coiled about said spring receiving post acting in substantially the line of movement of the nose of the shackle to expel the same, and limited in its movement by said bolt guiding post.

13. In a padlock, in combination, a casing, a shackle pivoted to said casing, a hub on said shackle concentric with its pivot, said hub having a flattened portion, a spring advanced reciprocable bolt in said casing having a portion adapted to contact with said flattened portion when the shackle is closed to lock the shackle and a recess into which a portion of the hub adjacent its flattened portion may swing when the bolt is

retracted, engagement of the hub with the wall of said recess maintaining the bolt in its retracted position.

14. In a padlock, in combination, an oscillating shackle, a reciprocating bolt for securing the shackle, means movable in the arc of a circle transversely into and out of the path of the bolt for holding the bolt in advanced position, a spring urging said means toward the path of the bolt, and key-releasable means for securing the last-named means in engagement with the bolt.

15. In a padlock, in combination, an operable shackle, a movable bolt for securing the shackle, means movable in the arc of a circle transversely into and out of the path of the bolt for holding the bolt in advanced position, a spring urging said means toward the path of the bolt, and key-releasable means for securing the last-named means in engagement with the bolt.

16. In a padlock, in combination, an operable shackle, a movable bolt for securing the shackle, means movable in the arc of a circle transversely into and out of the path of the bolt for holding the bolt in advanced position, and key-releasable means for positively securing the last-named means in engagement with the bolt.

NELS KROHN.
